UNITED STATES PATENT OFFICE

141,649

DESIGN FOR A BIB OR THE LIKE

Francis Patrick McSwiggen, Steubenville, Ohio

Application October 23, 1944, Serial No. 115,929

Term of patent 14 years

(Cl. D3—26)

To all whom it may concern:

Be it known that I, Francis Patrick McSwiggen, residing at Steubenville, in the county of Jefferson and State of Ohio, have invented a new, original, and ornamental Design for a Bib or the like, of which the following is a specification, reference being had to the accompanying drawings, forming part thereof.

Fig. 1 is a front elevational view of a bib showing my new design;

Fig. 2 is a top plan view thereof; and

Fig. 3 is a rear perspective view thereof, with the neckband fastened.

I claim:

The ornamental design for a bib or the like, as shown.

FRANCIS PATRICK McSWIGGEN.
